CLAIM

The ornamental design for a toilet bowl brush, substantially as shown.

DESCRIPTION

FIG. 1 is a top plan view of a toilet bowl brush, showing my new design;

FIG. 2 is a right side elevational view thereof, the left side being a mirror image thereof;

FIG. 3 is a bottom plan view thereof;

FIG. 4 is a front elevational view thereof;

FIG. 5 is a rear elevational view thereof;

FIG. 6 is an enlarged fragmentary view of the top end of the handle thereof;

FIG. 7 is an enlarged fragmentary view of the end of the handle adjacent to the pad portion.

FIG. 1

FIG. 2

FIG. 6

FIG. 3

FIG. 4

FIG. 7

FIG. 5
